Des. 186,244
Patented Sept. 29, 1959

186,244

COMBINED RECORD PLAYER AND SPEAKER SYSTEM

Arthur Steidinger, St. Georgen, Black Forest, Germany

Application May 22, 1958, Serial No. 51,023

Term of patent 14 years

(Cl. D56—4)

Fig. 1 is a front perspective view of a combined record player and speaker system showing my new design;

Fig. 2 is a rear perspective view thereof; and

Fig. 3 is a front perspective view thereof in operable position.

The dominant features of my new design reside in the portions shown in full lines.

I claim:

The ornamental design for a combined record player and speaker system, as shown and described,
